UNITED STATES PATENT OFFICE

ALDRICH M. BROWN, OF MOBILE, ALABAMA

COMBINED PUMP JACK AND HEAD

Application filed May 22, 1930. Serial No. 454,801.

This invention relates generally to pump jacks and has for its primary object to provide a combined pump jack and head of unitary construction which may be purchased as such, and which may be quickly and accurately attached to the upper end of the well casing without the services of a skilled mechanic or the aid of special tools.

Another object of the invention consists in the provision of such a device which while strong and durable is nevertheless of light and inexpensive construction and so designed as to avoid damage to the well casing on which it is directly mounted.

A further object of the invention resides in the provision of a pump jack composed of welded tubing, which not only permits of lightness in construction, but also provides simplicity and compactness in construction inasmuch as the tubing serves both as a support or frame and also as an air cushion or pressure regulator for the liquid drawn from the well.

Other objects and advantages of the invention will be apparent from the following description when taken in connection with the accompanying drawings, in which

Figure 1 is a front elevational view of the combined pump jack and head, parts being shown in section.

Figure 2 is a fragmentary side view of the jack standard, crank disc, and connecting rod.

Figure 3 is a side view of the apparatus taken at an angle of 90 degrees from Figure 1.

Figure 4 is a detail perspective view of the pump head, motor supporting brackets, etc.; and

Figure 5 is a fragmentary sectional view taken on line 5—5 of Figure 1.

Referring to the drawings in more detail, the numeral 1 indicates a conventional casing such as is used in oil wells, and the like, and the numeral 2 indicates a pump cylinder located in the casing at the desired distance below the surface. The present pump jack is designed to be attached directly to the upper end of the casing 1, and to this end the tubular member 3 is provided with threads 4 by means of which it may be attached to the cas-

ing through the medium of the coupling 5. It is to be understood, however, that any type of connection may be employed for securing the tubular member 3 to the well casing.

Welded to the upper end of the tubular member 3 is a cylindrical bearing member 6 of substantially less diameter than the tubular member 3. Within this bearing member 6 is reciprocably mounted a plunger 7, and a packing gland 8 is provided on the upper end of the bearing member to prevent leakage. The lower end of the plunger 7 is provided with a socket 9 adapted to receive the upper end of the conventional sucker rod 10 and set screws 11 are provided for securing the sucker rod within the socket.

Welded on one side of the tubular member 3 and in communication therewith is a tubular supporting bracket 12 which serves as a support for a tubular standard 13 which is in communication with the interior of the bracket 12 and is electrically welded thereto. The standard 13 serves as a support for the driving mechanism of the well pump and to this end a tubular bearing member 14 is welded onto the upper end of the standard 13 and has mounted therein a drive shaft 15. This drive shaft has fixedly secured to one end thereof a driving wheel 16 and on the other end a crank disc 17.

The driving wheel 16 is of fairly light construction and is driven by means of a belt 18 which is in turn driven by the rotor shaft of an electric motor 19. Motor 19 is preferably mounted on angle irons 20 welded to the tubular bracket 12 and it is to be noted that the pulley wheel on its drive shaft 21 is relatively small so as to reduce the speed of rotation of drive shaft 15 of the pump mechanism.

In order to maintain the belt 18 at the proper tension a belt tightener is provided and comprises an arm 22 pivoted to the standard 13 as indicated by the numeral 23 and provided with an idler pulley 24 which is caused to bear against the belt 18 by means of its spring 25.

As will appear hereinafter the hollow standard 13 must be air and liquid tight and in order to maintain this condition and at

the same time provide for pivoting the arm 22, a sleeve 26 passes through this tubular member and is welded at its opposite ends to the walls of the standard. This sleeve serves 5 as a bearing for the pivot shaft 27 of the belt tightener arm 22.

Connected to the crank disc 17 is a connecting rod 28 which has its opposite end pivotally connected to the upper end of the 10 plunger 7 and it will be noted that the crank disc 17 is provided with a plurality of apertures 29 arranged at varying radial distances from the center of the crank disc, so as to permit of mounting the connecting rod 28 to vary 15 the throw of the crank disc and consequently the length of stroke of the sucker rod.

As will appear as the description proceeds the hollow standard 13 serves not only as a support for the driving mechanism, but also 20 as a pressure regulator for the fluid pumped from the well. However, it is frequently desirable to improve a water system by adding a combined supply tank and pressure regulator, and such a device is indicated in Figure 1 as applied to the present construction. This combined storage tank and pressure regulator is indicated by the numeral 30 and is mounted on the pipe line 31 which is in communication with the tubular member 3 of 25 the combined pump jack and head. The first section of the pipe line 31 is threaded into a coupling 32 which is welded to the outside of the tubular member 3 and is in communication with the interior thereof. Any form 30 of connection may, of course, be provided for the supply tank and pressure regulator 30. In the present instance, however, this connection is shown as a T-coupling 33 disposed in the line 31 at a point adjacent the tubular 35 member 3. The tank 30 is provided with a pressure operated switch 34 of usual construction and adapted to open the circuit through the motor 19 when the pressure within the tank reaches that for which the pressure switch is set.

As already indicated the several elements of the head and frame are formed of tubular elements in communication with each other and having the joints welded. By this 50 design a very light and inexpensive construction is provided which is adaptable to be mounted on the upper end of the well casing without liability of damage thereto by vibration or undue stresses and strains. In 55 this connection it is to be noted that the standard 13 is supported on the tubular bracket 12 at a point very close to the axis of the tubular member 3 and the well casing, thus avoiding any undue strain on the casing 60 and related parts by the force applied to the connecting rod 28 when the apparatus is in operation.

It is to be noted also that the hollow standard 13 is in communication with the tubular 65 member 3 and hence with the interior of the

casing 1. Accordingly this member 13 serves not only as a support for the operating mechanisms of the jack, but also as a pressure regulator inasmuch as the liquid raised from the well will rise in the tube 13 to compress the air in the upper end thereof, and thus provide for a steady flow of fluid from the well.

In assembling the device, which may be purchased as a unit, the plunger 7 is disconnected from the connecting rod 28, removed from its bearing 6, and secured by means of socket 9 and set screws 11 to the upper end of the sucker rod 10. The bearing member 6 and its associated parts are then brought into position by threading the bearing member over the upper end of the plunger 7 and securing the connecting rod thereto. The lower end of the tubular member 3 is then secured to the upper end of the well casing as by means of the coupling member 5. It will thus appear that the entire device may be assembled in operative position without the use of special tools and without the aid of a skilled mechanic.

From the foregoing description taken in connection with the accompanying drawings it will be apparent that I have devised an exceedingly simple, light, and well balanced construction of pump jack and head; and that the standard 13 serves both as a support for the driving mechanism and also as a pressure regulator, thus providing both a compact and inexpensive type of construction.

In accordance with the patent statutes I have described what I now believe to be the best embodiment of my invention, but I do not wish to be understood thereby as limiting myself or the scope of the invention as many changes and modifications may be made without departing from the spirit of the invention; all such I aim to include within the scope of the appended claim.

What I claim is:

A pump jack including a tubular member adapted for attachment to the upper end of a well casing, a transversely arranged tubular supporting bracket secured to and in communication with said tubular member, a tubular standard mounted on and in communication with said supporting bracket, a driving wheel mounted on said standard, a motor, a driving belt connected to the motor shaft and driving wheel, a tubular bearing member extending transversely through said tubular standard and welded therein, and a belt tightener pivotally mounted in said bearing.

ALDRICH M. BROWN.
